 corporation of New Jersey

Application December 24, 1937, Serial No. 181,656

15 Claims.

(Cl. 230—5)

This invention relates to regulators for motor driven fluid compressors, and more particularly to a regulator wherein the speed of the motor is operated at either maximum speed or minimum speed in accordance with the output of the compressor.

A motor driven unit of this sort comprises a fluid compressor driven by a motor or engine, such as an internal combustion motor or a steam engine, and a receiver tank to receive and store the fluid under pressure discharged by the compressor. In the operation of the unit, the discharge of fluid to the receiver continues until the pressure therein reaches a predetermined amount, whereupon, a device provided on the compressor operates to prevent further discharge of fluid to the receiver tank (commonly termed "unloading") and, at the same time, decelerates the compressor driving motor to its minimum, or idling, speed. The compressor then continues to operate in this manner until the pressure in the receiver tank falls to a predetermined minimum point and then the device operates to permit the compressor to again discharge fluid to the receiver tank (commonly termed "reloading"), and to accelerate the motor to its maximum operating speed.

With this mode of operation the compressor, under light loads, will fluctuate rapidly between its minimum, or idling, speed and its maximum speed, resulting in inefficient and ineconomical operation of the unit.

It is, accordingly, an object of the present invention to provide a means whereby a motor driven compressor unit may reload while the motor is operating at its minimum speed.

It is a further object to provide means whereby, under light loads, it is impossible to reload the compressor at the maximum motor speed until a predetermined minimum discharge pressure of the compressor is reached.

A still further object is to provide means whereby the motor can not accelerate to its maximum speed to reload the compressor, under light loads, until a predetermined minimum pressure is reached in the receiver and then only after a predetermined time delay.

It is a still further object to provide a device whereby resumption of maximum motor speed, after reloading, is prevented under light loads and permitted when reloading occurs under heavy loads.

Another object is to provide a device for controlling the speed setting of the governor in ac-

cordance with variations in the discharge pressure of the compressor.

Another object is to provide a regulating device varying in accordance with the discharge pressure of the compressor whereby, on the occurrence of a predetermined high discharge pressure, the motor speed is reduced from the maximum speed to the minimum speed; of a predetermined maximum pressure, the compressor unloads; of a predetermined low pressure, the compressor reloads; and of a predetermined minimum pressure, the motor accelerates from the minimum motor speed to the maximum motor speed.

These and other objects will be readily apparent from the following specification of which the drawings form a part and in which

Figure 1 is a view partly in elevation and partly in section illustrating the application of the present invention to a compressor unit, and in which the view of the governor is increased in size in order to bring out the details more clearly.

Figure 2 illustrates in section the loading device shown in Fig. 1, and

Figure 3 is a view partly in elevation and partly in section of part of the governor controlling device constructed in accordance with the principles of this invention.

It will be noted by referring to Fig. 1 that the compressor unit consists of a fluid compressor 1 mounted on a frame 3 supported by wheels 5. The frame 3 also supports an internal combustion engine 7 directly connected to drive the fluid compressor 1. Fluid to be compressed by the compressor 1 is supplied by the inlet conduit 9 and the conduit 11 delivers the compressed fluid discharged from the compressor to the receiver tank 13.

The inlet conduit 9 contains a means to unload and reload 15 which is illustrated in detail in Fig. 2. This device consists of a casing 17 connected to the conduit 9 at its upper end and to the compressor 1 at its lower end. The casing is so designed that a portion of the wall extends within the outer walls thereof and forms valve guides 19 for the balanced cylindrical reciprocating valve 21. A plate 23 closes an opening 24 in the side wall of the casing 17 and is provided with a recess 26 in which rests a spring 25, normally urging the cylindrical valve 21 towards the right or open position. With the valve in the open position shown in Fig. 2, it is readily apparent that fluid may enter through the conduit 9, pass around the valve 21 and flow into the compressor.

- Secured to the casing 17 on the side opposite to the plate 23 is a piston chamber 27 having a piston 29 therein. One end 31 of the piston chamber 27 forms a seat for the valve 21 when the valve is in its open, or right hand, position. The piston 29 is adapted to reciprocate in the piston chamber and to transmit its motion to the valve 21 by bearing on the pin 33 formed as an integral part of the cylindrical valve 21.
- When the pressure exerted by the piston 29 on the valve 21 is sufficient to overcome the force of the spring 25, the cylindrical valve 21 will be moved away from its seat 31. Movement of the valve from its seat will shut off communication between the inlet conduit 9 and the compressor 1 when the ribs 35 are moved into alignment with the walls of the casing 17, which form the guides 19 for the valve 21.
- At one side of the piston chamber 27 and communicating therewith is a pressure operated auxiliary valve, generally designated as 36. This valve serves to control the admission of pressure fluid to the piston chamber, and thus the movement of the piston against the force of the spring 25. The auxiliary valve 36 comprises a valve body 37 communicating directly with the receiver tank 13 through the conduit 39. In order to prevent continuous communication between the receiver tank and the piston chamber 27 an auxiliary valve proper 41 is normally pressed on the seat 43 by the member 45. As is apparent from the figure, the member 45 transmits the pressure of the spring 47, which is compressed between this member and the bushing 49.
- In the event that the pressure in the receiver tank is sufficient to move the auxiliary valve proper 41 from its seat 43 against the compressive force of the spring 47, a second seat 51 is provided by inserting a bushing 53 in the auxiliary valve body 37 and providing the valve 41 with an appropriate face to rest on this seat. By adjusting the bushing 49, the compression of the spring 47 may be increased or decreased, and the pressure at which the valve 41 will leave its seat 43 and seek its seat 51 may thus be predetermined, and also the pressure at which the valve 41 returns to its seat 43.
- From the above description it will be seen that when the pressure in the receiver reaches a predetermined point, which is sufficient to overcome the compressive force of the spring 47, the valve 41 will open, thereby permitting fluid to flow past the valve seat 43, through the channel 55, into the piston chamber 27, and cause the piston to push the cylindrical valve to its closed position. The pressure which is necessary to open the valve 41 is greater than that required to maintain the valve open, since the effective pressure area of the valve is increased by the portion of the diametrical area of the valve which seats on the seat 43 when the valve is closed.
- However, when the pressure falls sufficiently so that the spring 41 can return the valve 41 to its seat 43, the fluid trapped in the chamber 27 must be allowed to escape. This is accomplished by permitting the fluid to flow through the channel 55, by the seat 51, and through a central opening 57, in the bushing 49, surrounding the member 45 to the atmosphere. When the fluid has been exhausted from the piston chamber, the compressive force of the spring 25 will move the cylindrical valve 21 from its closed position to its open position and return the valve 21 to its seat 31.
- By way of summarizing the action of this de-

vice, it may be said that when the pressure in the receiver tank reaches a predetermined point the auxiliary valve opens and permits the fluid pressure to close the cylindrical valve to unload the machine. When the pressure has fallen to a predetermined low point, the auxiliary valve closes, the fluid pressure escapes from the piston chamber and the cylindrical valve opens to again reload the compressor.

With reference to Fig. 1 the speed of the internal combustion motor is controlled by a governor, generally indicated at 59, which consists of a shaft 61 directly connected to the shaft (not shown) of the engine. A gear 63 secured to a flange on the shaft 61 is provided with ears 65 on which are fulcrumed weights 67. When the engine rotates, the centrifugal force moves the weights away from the shaft 61 in accordance with the speed of the motor, until they reach their outermost position at which time they act to prevent further increase in the speed of the motor. Rollers 69 mounted on the weights 67 bear against a plate 71 surrounding an extension on the shaft 61. Hence, as the weights move outwardly the governor spring 89 is compressed and the motion of the plate 71 is transmitted, through an anti-friction bearing 73, to a plate 75, formed integrally with the pin 77 coaxial with and slidably mounted on the shaft 61.

The plate 75 is provided with a clevis 79 surrounding and pinned to lever 81 fulcrumed on the motor frame at 83. At the opposite end of the lever 81, is a tie-rod 85 which controls the butterfly valve 87, in the fuel intake of the engine. In decreasing the speed of the motor, the movement of the weights 67 inwardly toward the shaft 61, moves the plate 71 in the same direction, thus pivoting the lever 81 about its fulcrum 83 and moving the butterfly valve 87 by means of the rod 85 toward the open position to accelerate the motor. Conversely, when the speed of the engine is increased, the lever 81 and rod 85, under the influence of the spring 89, move the butterfly valve in the opposite direction to decrease the fuel supply to the motor.

As is customary in centrifugal governors, the weights 67 are resiliently held in their retracted position and to this end a spring 89 is provided. This spring is housed in a casing 91 secured to the frame of the motor and having a bore 93 extending therethrough. The bore communicates at one end with a recess 95 in which the spring is contained and has a plunger 97 extending therethrough and provided with a flange against which one end of the spring 89 rests. The other end of the spring pushes a member 99 against the projection 101 formed on the lever 81.

The external end of the plunger 97 bears against a hooked lever 103, fulcrumed on the casing 91, and is adapted to transmit force to 60 compress the spring 89. The speed setting of the governor is determined by the amount of the force the weights 67 must exert to move the plate 71. Hence, if the hooked lever forces the plunger 97 to compress the spring to the compression 65 limit, a much greater speed of the motor will be necessary in order that the centrifugal force of the weights 67 shall be sufficient to move the plate 71 outwardly from the shaft against the resistance of the spring 89. Under these conditions, consequently, the plate 71, the lever 81, and rod 85, will not be moved to throttle and decrease the speed of the motor until the speed of the motor exceeds the maximum speed at which it is desired to operate the motor.

Conversely, if the hooked lever 103 is moved so that the spring 89 may expand, move the plunger 97 to the left, the plate 11 may be moved out from the shaft 61 by the weights 67 when the motor is running at a much slower rate. The result is that the motor will operate at a greatly reduced speed and a slight increase in speed will cause the weights to move the plate 11 further away from the shaft thereby throttling the motor intake and decreasing the speed to the desired minimum.

Thus, if the position of the hooked lever 103 is regulated, the speed setting of the governor may be regulated, and for that reason a pressure responsive device having two control positions is connected to this lever by the tie-rod 105.

The details of the regulating mechanism are best illustrated by reference to Fig. 3. The regulating mechanism consists of a chambered casting 107, having a bore 109 communicating with the piston chamber 111. The piston 113 in the chamber is secured to a shaft 115 extending through the bore 109 and connected to the lever 117 fulcrumed on the frame of the motor at 119. At the end of the lever opposite to that on which the shaft 115 is secured, is the tie-rod 105 which connects with the hooked lever 103. In one end of the chamber 111 is a recess 121 in which rests a spring 123 bearing against the piston 113 and normally urging it toward the right.

The end of the chambered casing 107 is closed by a plate 125 suitably secured thereto. A conduit 127 extends through this plate into the piston chamber 111 and bears against the piston 113. Slots 129 are provided in the end of the conduit which bears against the piston to provide a large opening into the piston chamber. This conduit communicates with a means responsive to the discharge pressure such as an auxiliary valve mechanism, generally indicated at 131, which is similar in construction to the auxiliary valve mechanism 36 described in connection with the unloading and reloading device, and also communicates with the receiver tank by means of the conduit 133.

Since the structural features of the auxiliary valve mechanism 131 are similar to those of the auxiliary valve mechanism 36, described in connection with the unloading and reloading device, the same numerals with a numeral 1 added as a suffix are used to indicate similar parts, and description of the auxiliary valve 131 will be dispensed with. Likewise the operation of this valve is the same as the operation of the previously described valve, except for the fact that different receiver pressures are employed to open and close the valve. The regulation of the pressures, of course, being accomplished by varying the compressive force of the spring 47.

During the operation of the compressor the valve 131 will remain closed during the initial period of loading the receiver. However, when the pressure in the receiver tank rises to a point where it is sufficient to move the valve 411 from its seat 431 against the compression of the spring 471, fluid will flow from the receiver tank past the seat 431, into the conduit 127, and escape into the piston chamber 111 thereby exerting pressure on the piston 113 and moving the piston against the compression of spring 123 toward the left. The movement of the piston is transmitted to the lever 117 by the shaft 115 and consequent movement of the tie-rod 105 will move

the hooked lever away from the plunger 97 and permit the spring 89 to expand.

Releasing the compressive force on the spring 89 permits the lug 101, bearing against the member 99, to move further to the left with the result that the butterfly valve 87 closes. The motor will then operate at its minimum speed as was previously explained. This state continues so long as the valve 411 is resting on its seat 511 and allowing the passage of fluid from the receiver tank by the seat 431. When the pressure in the receiver tank begins to fall the valve will remain open until the pressure on the valve 411 is no longer sufficient to overcome the compressive force exerted by the spring 471.

The pressure required to hold the valve open is considerably less than the pressure required to open the valve. This will be readily apparent when it is noted that the effective pressure area is increased to the total diametrical area of the valve 411, as was pointed out in the description of valve 41 in the auxiliary valve 36. Upon the closing of the valve 411, shutting off the flow of fluid under pressure from the receiver to the piston chamber, the piston does not immediately move from its left-hand position back to the normal unactuated position at the right of the chamber. This is due to the fact that fluid under pressure remains in the chamber when the valve 411 closes and, accordingly an escape for the fluid in the chamber is provided, similar to the escape provided with the unloading and reloading device 36.

The path for the escape of fluid is, consequently, through the slots 129, into the conduit 127, past the seat 511, through the channel 511, to the atmosphere. With this arrangement the piston chamber is normally open to atmospheric pressure and it is only when the predetermined high pressure occurs in the receiver tank that fluid is admitted therefrom to the piston chamber, and at that time the atmospheric vent is closed by the valve 411 as it rests on the seat 511.

In the operation of the entire regulating means the predetermined high pressure at which the auxiliary valve 131 opens is slightly less than the maximum allowable pressure at which the auxiliary valve 36 opens. For example, the valve 131 may open at 100 pounds per square inch and the valve 36 at 105 pounds per square inch. The regulation of these pressures, of course, depends upon the will of the operator who may vary the compressive force of the springs 47 or 471 in the manner described. As the opening pressures for the respective valves are different, in accordance with this invention the corresponding closing pressures are adjusted to be different. Thus the corresponding closing predetermined low pressure for the auxiliary valve 36 may be 85 pounds per square inch, whereas the corresponding closing, or predetermined minimum, pressure for the auxiliary valve 131 may be 80 pounds per square inch.

In general the operation of the unit is as follows: When the machine is started, assuming no pressure at the receiver, both of the auxiliary valves 36 and 131 are closed leaving the unloader valve 21 in its open position and the piston 113 in its right-hand position, corresponding to the maximum speed setting of the motor governor. When the pressure builds up to the 100 pounds per square inch, the valve 411 opens, the piston 113 moves to its left-hand position and changes the governor speed setting to the minimum speed.

If the load is constant, the compressor will then operate to supply the necessary require- 75

- ments at the minimum speed of the motor. If the pressure should continue to build up in the receiver to the maximum allowable pressure, 105 pounds per square inch, the valve 41 operates to close the unloading valve 21 and thereby prevents further discharge of air to the receiver. If the load now increases, the pressure in the receiver tank will fall and when it reaches 85 pounds per square inch, the valve 41 closes and 10 the unloading valve 21 opens again permitting the discharge of air from the compressor to the receiver. So long as the load does not increase to the point where the pressure in the receiver tank falls to 80 pounds per square inch, the valve 41 remains open and the machine will continue to operate at minimum speed. Should the load increase, however, and the pressure fall to the minimum allowable pressure of 80 pounds per square inch, the valve 41 will close, permitting 15 the fluid in the chamber 111 to escape to atmosphere and the piston to move to its right-hand position thus causing the motor again to accelerate to its maximum speed.
- It is thus apparent that during the operation 20 of the compressor the regulating means will operate to maintain the motor running at minimum speed so long as the load does not require the motor to run at maximum speed, and the cycle of operation will be similar to that described.
- 30 It is understood that the construction above described is a preferred embodiment of the invention and that many changes which do not depart from the scope and spirit of the invention will occur to those skilled in the art.
- 35 I claim:
1. In a regulator for a motor driven fluid compressor having a speed governor, a compressor discharge controlled pressure responsive device for controlling the speed setting of the governor 40 having two control positions, means to unload the compressor at a predetermined maximum discharge pressure and to reload the compressor at a predetermined low discharge pressure, and means responsive to a predetermined high discharge pressure intermediate the maximum and low discharge pressures to enable the discharge pressure to set and maintain the pressure responsive device in one control position until a predetermined minimum discharge pressure less than said low discharge pressure is reached.
  2. In a regulator for a motor driven fluid compressor having a fluid receiver tank and a speed governor, a pressure device for controlling the speed setting of the governor actuated by 55 the fluid pressure in the receiver tank, means to unload the compressor at a predetermined maximum pressure in the receiver tank and to reload the compressor at a predetermined low pressure in the receiver tank, means responsive to a predetermined high pressure intermediate the maximum and low pressures in the receiver tank to admit fluid therefrom to the pressure device and responsive to a predetermined minimum pressure less than the low pressure in the receiver tank to 60 prevent admission of fluid therefrom to the pressure device, and means to regulate the predetermined high and predetermined minimum pressures.
  3. In a regulator for a motor driven fluid compressor having a fluid receiver tank and a speed governor, a pressure operated device for controlling the speed setting of the governor in accordance with the fluid pressure in the receiver tank having a maximum speed setting position and 65 a minimum speed setting position, means to un-
- load the compressor at a predetermined maximum pressure in the receiver tank and to reload the compressor at a predetermined low pressure in the receiver tank, means normally preventing admission of fluid from the receiver tank to the pressure responsive device to enable said pressure responsive device to remain at its maximum speed setting position and adapted to admit fluid to said pressure responsive device when a predetermined high pressure intermediate the predetermined maximum and low pressures is reached until a predetermined minimum pressure less than the predetermined low pressure is reached to change said pressure responsive device to and maintain it at the minimum speed setting position.
4. In a regulator for a motor driven fluid compressor adapted to discharge fluid under pressure to a receiving means and having a speed control governor, means to unload the compressor at a predetermined maximum discharge pressure and to reload the compressor at a predetermined low discharge pressure, pressure means in communication with the receiving means to control the speed setting of the governor, and means normally preventing communication between said pressure means and the receiving means adapted to permit communication with the pressure in the receiving means is within a predetermined range after a predetermined high pressure intermediate said maximum and low pressures has been reached.
5. A regulator for a motor driven fluid compressor having a governor, a pressure responsive device for controlling the speed setting of the governor in accordance with variations in the discharge pressure of the compressor having two control positions, means to unload the compressor at a predetermined maximum pressure and to reload the compressor at a predetermined low discharge pressure, adjustable means to predetermine the discharge pressures at which the last said means operates, means to render the pressure responsive device operative to assume one control position at a predetermined high pressure intermediate said maximum and low pressures and to assume the other control position when a predetermined minimum pressure less than said low pressure is reached, and adjustable means to regulate the pressures at which the last said means operates.
6. A regulator for a motor driven fluid compressor having a governor, a pressure responsive device for controlling the speed setting of the governor in accordance with variations in the discharge pressure of the compressor having two control positions, means to unload the compressor at a predetermined maximum discharge pressure and to reload the compressor at a predetermined low discharge pressure, adjustable means to predetermine the pressure at which the last said means operates, and means to render the pressure responsive device operative to assume one control position at a predetermined high discharge pressure intermediate said predetermined maximum and predetermined low discharge pressures and to assume the other control position at a predetermined minimum discharge pressure less than said predetermined low discharge pressure, means to predetermine the pressures at which the last said means operates, and means associated with the last said means to normally subject the pressure responsive device to atmospheric pressure.
7. A regulator for a motor driven fluid com-

pressor having a governor, a pressure responsive device for controlling the speed setting of the governor in accordance with variations in the discharge pressure of the compressor having a maximum speed setting position and a minimum speed setting position and normally maintaining the governor at maximum speed setting, means to unload the compressor at a predetermined maximum discharge pressure and to reload the compressor at a predetermined low discharge pressure, means to render the pressure responsive device operative to change the governor to the minimum speed setting at a predetermined high pressure intermediate said predetermined maximum and low discharge pressures and maintaining that speed setting within a predetermined lower range of discharge pressures, and means associated with the last said means to subject the pressure responsive device to atmospheric pressure when the discharge pressure is outside said predetermined range.

8. A regulator for a motor driven fluid compressor having a speed governor comprising a pressure responsive device for controlling the speed of the governor in accordance with variations in the discharge pressure of the compressor having a maximum speed setting position and a minimum speed setting position, means to normally maintain the governor at a maximum speed setting, means to unload the compressor at a maximum discharge pressure and to reload the compressor at a predetermined low discharge pressure, means to render the pressure responsive device operative at a predetermined high pressure intermediate said maximum and low discharge pressures to cause the governor to adjust and maintain the motor speed at a minimum and to render the pressure responsive device inoperative to cause the governor to accelerate the speed of the motor to a maximum when a predetermined minimum discharge pressure less than said low discharge pressure is reached.

9. A regulator for a motor driven fluid compressor having a governor comprising a pressure responsive device actuated in accordance with variations in the discharge pressure of the compressor normally positioned to maintain the governor at the maximum speed setting and having a minimum speed setting position, means to unload the compressor at a predetermined maximum discharge pressure and to reload the compressor at a predetermined low discharge pressure, means responsive to a predetermined high discharge pressure intermediate said predetermined maximum and predetermined low discharge pressures to render said pressure responsive device operative to move to its minimum speed setting position thereby changing the governor to its minimum speed setting.

10. In a governor speed regulator for a motor driven fluid compressor, a pressure responsive device having maximum and minimum speed setting positions for controlling the governor in accordance with variations in the discharge pressure of the compressor, means to unload the compressor at a predetermined maximum discharge pressure and means to reload the compressor at a predetermined low discharge pressure, and means normally maintaining the pressure responsive device in the maximum speed setting position until a predetermined high pressure intermediate said predetermined maximum and low discharge pressures is reached.

11. In a governor speed regulator for a motor driven fluid compressor, a pressure responsive

device having a maximum speed setting position and a minimum speed setting position for controlling the governor in accordance with variations in the discharge pressure of the compressor, means to unload the compressor at a predetermined maximum discharge pressure and means to reload the compressor at a predetermined low discharge pressure, means responsive to the discharge pressure of the compressor normally preventing movement of the pressure responsive device from its maximum speed setting position to effect movement of the pressure responsive device to its minimum speed setting position when a predetermined high pressure intermediate said predetermined maximum and predetermined low discharge pressures is reached, and means to predetermine said high pressure.

12. In a governor speed regulator for a motor driven fluid compressor having a receiver tank, means to unload the compressor at a predetermined maximum discharge pressure and means to reload the compressor at a predetermined low discharge pressure, a casing containing a chamber, a piston in the chamber, a spring normally preventing movement of the piston, a series of interconnected levers for transmitting movement of the piston to the governor, a second casing having a chamber communicating with the receiver tank, a conduit connecting the two casings, a piston in the second chamber, a piston seat in the chamber, a spring normally holding the piston against the seat to prevent communication between the receiver and the first chamber, means to adjust the tension on the spring whereby the piston in the second chamber may be moved from its seat by a predetermined high pressure intermediate said predetermined maximum and low discharge pressures in the receiver to permit the pressure in the receiver to move the piston in the first said chamber against the tension of its spring and to reseat upon occurrence of a predetermined minimum pressure less than said predetermined low pressure in the receiver, means to vent the first chamber through the second chamber when its piston is seated, and means to prevent venting when the piston is unseated.

13. In a regulator for a motor driven fluid compressor having a speed governing means, compressor discharge pressure actuated control means for the speed governing means receiving fluid discharged by the compressor, means to unload and reload the compressor in accordance with variations in the compressor discharge pressure, and means to prevent the pressure actuated control means from receiving compressor discharge fluid until the compressor discharge fluid pressure reaches a predetermined pressure less than the compressor unloading pressure.

14. In a regulator for a motor driven fluid compressor having a speed governor and a receiver tank comprising means to unload the compressor at a predetermined maximum discharge pressure and to reload the compressor at a predetermined low discharge pressure, and a pressure responsive device having a maximum speed setting position and a minimum speed setting position comprising means defining a chamber communicating with the receiver, a piston in the chamber, means to transmit movement of the piston to the governor, a spring to normally maintain the piston in the maximum speed setting position, means normally preventing communication between the receiver and chamber adapted to permit communication when the pressure in the receiver

75

reaches a predetermined high pressure and until a predetermined minimum pressure is reached whereby the piston may move into its minimum speed setting position with respect to the governor.

- 5 15. In a regulator for a motor driven fluid compressor having a governor and a receiver tank including means to unload the compressor at a predetermined maximum discharge pressure and to reload the compressor at a predetermined low discharge pressure, and a pressure responsive device having a maximum speed setting position and a minimum speed setting position comprising means defining a chamber communi-

cating with the receiver, pressure responsive means in the chamber, means to transmit movement of the pressure responsive device to the governor, means to normally maintain the pressure responsive device in its maximum speed setting position, means normally preventing communication between the receiver and chamber adapted to permit communication within a predetermined pressure range after a predetermined high discharge pressure less than the predetermined maximum discharge pressure has been reached, and means to predetermine said range.

10 ALLAN O. CARPENTER.
